UNITED STATES PATENT OFFICE.

HARRY Y. HADEN, OF NEW YORK, N. Y.

FIRE-FIGHTING BOAT.

Application filed April 7, 1927. Serial No. 181,707.

My present invention relates more particularly to the motive power and pumping systems of boats of the above type, and more particularly to special adaptation of motive power to the propelling system. In boats of the above type, it is common to use the same motor means, either steam engine, or preferably a Diesel internal combustion engine, both for operating the pumps to fight the fire and for driving the propeller to move the boat from place to place. It is also common to use the steam turbine and electric drive propelling system in which the generators for supplying the propelling 10 motors are driven by the same turbines that supply the fire pumps as in the patent to Babcock No. 924,128, granted June 8, 1909. The use of the motor in connection with two different sets of mechanism for two different purposes involves complications which it is the object of my present invention to avoid. For instance, in the Babcock apparatus above specified, the propelling generators and motors are very expensive, the screw propellers are always in danger of breakage from debris found adjacent a fire end, as stated in the patent, the fire fighting pumps have to be put out of commission and drained whenever full propelling speed is required. 20 As will be seen from the following description, my invention involves the discovery that where rotary pumps are used, two or more in series, to supply all of the fire fighting nozzles, a connection of the same pumps in parallel will give the proper volume and velocity for propulsion by means of submerged rearwardly directed bow jets, the pumps being continuously operated at a designed normal power output. 30 My present invention contemplates utilizing the motor through the pumps, the propulsion of the boat being by water jets used in accordance with the principles set forth in patents and applications of Clifford M. Paxton, particularly United States Patent No. 1,543,026, granted June 30, 1925. According to this method, the propulsion is by means of sheet jets from nozzles located on the bow in advance of and discharging 40 through the region of the under-water body of the ship, beneath where the maximum bow wave tends to pile up, when the ship is proceeding at speed. While it is theoretically possible to use the fire fighting pressure for propulsion in accordance with the 50 above method, it will be found that in general the great pressures, high velocity and small volume of the jets required for fire fighting are not suitable for efficient propulsion of the boat in accordance with the principles 60 employed by Paxton. In boats of the sizes and draft commonly employed for fire fighting, "fitting" the bow jets for the shape and design speed of the hull will, in general, require much lower pressures and larger volumes of water than required for fire fighting. 65 In this situation, my invention contemplates the employment of two or more pumps adapted to operate efficiently at the normal full speed of the engine, each pump being 70 adapted to deliver water at the lower pressure required for the jet propulsion, the fire fighting pressures being attained by connecting two or more of said pumps in series. 75 For instance, the engine may be a Diesel internal combustion engine of the motor cylinder type, giving say 600 horse power at normal operating speed of 300 revolutions per minute. Such an engine may be connected to drive, say, 4 centrifugal pumps 80 through an intermediate gearing designed to step up the rotation to the desired higher speed required for efficient operation of said pumps. Each of these pumps may have a capacity of, say, 2500 gallons per minute 85 against 75 pounds back pressure. Normally, all the pumps are operated in parallel to supply a distributing main supplying the bow jets and preferably also laterally directed manoeuvring jets. The same main is connected to the fire fighting nozzles on the deck. 90 Normally, for propelling purposes, 4 such pumps operating in parallel will deliver 10,000 gallons per minute at 75 pounds pressure. This is a suitable volume and pressure 95 for propulsion. 100 For fire fighting, however, two pumps may be connected in series, the result being an output of approximately 5000 gallons per minute against 150 pounds pressure. The advantage of this scheme is that the pumps may be installed with permanent series parallel connections, controlled by valves which may be electrically operated from the central station to instantly change from fire fighting pressure to propulsion pressure, 105 similar valves in the propulsion or manoeuvring system being similarly controlled. 110 The above and other features of my invention will be more evident from the fol-

lowing description in connection with the accompanying drawings, in which:

Fig. 1 is a diagrammatic plan view of a power pumping outfit and distributing system for jet propulsion and manoeuvring as well as for fire fighting;

Fig. 2 is a side elevation of a fire boat, the side of the boat being broken away to show the essential parts of the equipment 10 along the dotted line 2-2, Fig. 1.

In these drawings, the hull 1 is equipped with a motor 2 which, as above stated, may be a multi-cylinder Diesel oil engine operating through the usual multiplying gear diagrammatically indicated at 3 to drive two parallel shafts, 4, 4^a, each equipped with two centrifugal pumps 5, 5^a and 5^b, 5^c. The intakes of these pumps are supplied through scoops 6, 6^a, which are deeply submerged, 15 and they deliver to a fore and aft distributing main 7, extending forward to the propelling nozzles 8, 8^a at the bow. Rearwardly, the main is preferably divided into parallel conduits 7^a, 7^b, uniting in a rearward extension, 7^c. The forward main may be connected, as in the Paxton system, for supplying forward diagonally directed manoeuvring nozzles, 9, 9^a and the rearwardly 20 extending main, 7^c, with symmetrically and 25 oppositely directed manoeuvring nozzles 10, 10^a.

The fire nozzles with the usual control means, are mounted on the deck in convenient locations, as 11, 11, etc., supplied 30 through vertical pipes supplied directly from the main, in the present case two from each of the parallel pipes 7^a, 7^b, and three from the rear extension 7^c.

It will be understood that all parts of 40 the above described distributing system are controlled by suitably located valves, preferably power operated, as for instance, valve 12 for the bow jets, 13, 13^a for the forward manoeuvring nozzles and 14, 14^a for the aft 45 manoeuvring nozzles. The engine 2 and multiplying gear 3 need not be further described other than to say that the multiplying gear is a double helical gear, driving two pinions, and is of construction well known 50 in the art for stepping up the speed of a slow speed engine, to suit the requirements of a centrifugal pump. Similarly, the pumps need not be particularly described, 55 because they are well known.

The novel requirements of my present invention, however, are that the pumps be 60 designed to operate efficiently at the efficient speed of the engine and that at such speed each pump will operate to deliver the maximum amount of water at the relatively low pressure desired for propulsion. Then for 65 series operation, to deliver less water at higher pressure, I provide a cross-connecting pipe 20 from the output of pump 5^a to the intake of pump 5 and pipe 20^a from

the output of pump 5^b to the intake of pump 5^c, the pipe 20 being controlled by valve 21 and pipe 20^a by valve 21^a. There is also a valve, 22, to cut off the output of pump 5^a from the main 7; also valve 22^a to 70 cut off the output of pump 5^b from said main 7; also a valve 23 to cut off the intake of pump 5 from scoop 6; also valve 23^a to cut off the intake of pump 5^c from scoop 6^a.

In operation, valves 21, 21^a of the series 75 connecting pipes 20, 20^a being closed and valves 22, 22^a, 23, 23^a, being open, the four pumps will operate in parallel, each independently, to supply its 2500 gallons per minute against 75 pounds pressure; or the 80 valves 21, 21^a being opened and the other four valves closed, pumps 5^a and 5^b will operate in series and pumps 5^c, 5^d will operate in series, each pair of pumps thus operating 85 in parallel to supply 2500 gallons per pair against 150 pounds pressure.

As these valves are operated in sets, certain ones opening when others close, it is evident they may be interdependently operated by mechanically or electrically interlocking control systems well known in the art. One obvious interdependence is to make valves 22, 22^a as "three-way" valves, thereby dispensing with valves 21, 21^a, respectively. It may be noted that for efficient 95 operation, these pumps must run at high speed, say 1700 revolutions per minute, which is a desirable speed for an electric generator G, that may be coupled directly to the end of pump shaft 4, to supply the 100 electrical system of the boat.

I am aware that many jet propulsion schemes for boats have been proposed and that pumps used for such purpose may be used without any change in speed or output, 105 to pump bilge water from the hold in case of disaster or bad leaks or to flood the hold in case of fire but in none of these prior devices has there been any provision or even consideration of the desirability of, or the 110 means for pumping the water at previously predetermined volumes and velocity required for efficient jet propulsion, much less in design of the boat and its propulsion means so that the same pumps, operated at constant 115 load are exactly right for the jet propulsion when pumping in parallel and exactly right for the fire fighting when pumping in series.

I claim:

1. A fire boat, including fire extinguishing nozzles and jet propulsion nozzles in combination with an engine, centrifugal pumps and a distributing system for supplying both kinds of nozzles, said engine being of the heavy duty slow speed type, operating through a multiplying gear to drive two or more centrifugal pumps at normal full speed for supplying both kinds of nozzles, said pumps being each designed for maximum output at pressures suitable for 120 125 130 135 140 145 150 155 160 165 170 175 180 185 190 195 200

the jet propulsion and equipped for connection of two or more pumps in series to furnish higher pressures for fire fighting.

2. A fire boat, including fire extinguishing nozzles and jet propulsion nozzles in combination with an engine, centrifugal pumps and a distributing system for supplying both kinds of nozzles, said engine being of the heavy duty slow speed type, 10 operating through a multiplying gear to drive two shafts on each of which shafts at least two of the pumps are mounted, pumps on the same shaft being connected and valved for either parallel or series operation.

15 3. A fire boat, including fire extinguishing nozzles and jet propulsion nozzles in combination with an engine, centrifugal pumps and a distributing system for supplying both kinds of nozzles, said pumps being each 20 designed for maximum output at pressures suitable for the jet propulsion and equipped for connection of two or more pumps in series to furnish higher pressures for fire fighting.

25 4. A fire boat, including fire extinguishing nozzles and jet propulsion nozzles in combination with an engine, centrifugal pumps and a distributing system for supplying all of said nozzles.

30 5. A fire boat, having an electrical system, a fire fighting system including exterior fire extinguishing nozzles and jet propulsion nozzles in combination with an engine, centrifugal pumps and a distributing system 35 for supplying both kinds of nozzles, said engine being of the heavy duty slow speed

type, operating through a multiplying gear to drive at least two centrifugal pumps at normal full speed and connected for parallel operation to supply said propulsion nozzles 40 at the required volume and velocity and in series to supply said fire extinguishing nozzles at correspondingly higher pressure and less volume, and an electric generator for said electric system designed for efficient operation 45 at the normal full speed of said pumps and directly driven by the pump shaft.

6. A fire boat equipped with a set of exterior nozzles designed according to fire engine principles to discharge streams of high 50 velocity, long range and large volume to fight distant fires, and a set of bow jet nozzles designed to discharge streams of such surface area as to fit the hull at designed full speed when supplied at pressure 55 approximately one-half or less than that required for the fire nozzles, in combination with a single system for supplying both sets of nozzles each at their designed pressures, said means including at least two centrifugal 60 pumps and means for driving them at approximately the same normal full speed, said pumps being designed for parallel connection and when so connected, to supply said propulsion nozzles at the required volume 65 and velocity, or in series, to supply said fire nozzles at correspondingly higher velocity and less volume.

Signed at New York city in the county of New York and State of New York this 70 5th day of April, A. D. 1927.

HARRY Y. HADEN.
